Primary Examiner — Katie Jane Stofko(74) *Attorney, Agent, or Firm* — Ryan T. Grace; Advent,
LLP(57) **CLAIM**The ornamental design for a cut potato product, as shown
and described.**DESCRIPTION**FIG. 1 is a front, top, left side perspective view of a cut
potato product;

FIG. 2 is a bottom, front, right side perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The evenly-spaced broken lines shown in FIGS. 1–8 illus-
trate portions of the cut potato product that form no part of
the claimed design. The dash-dot-dash broken lines shown
in FIGS. 1–8 illustrate the boundary of the claimed design
which forms no part thereof.**1 Claim, 5 Drawing Sheets**| (56)	References Cited
